UNITED STATES PATENT OFFICE.

FREDERICK A. NELSON, OF WESTFIELD, MASSACHUSETTS.

HAMMOCK.

SPECIFICATION forming part of Letters Patent No. 269,876, dated January 2, 1883.

Application filed June 5, 1882. (No model.)

To all whom it may concern:

Be it known that I, FREDERICK A. NELSON, of Westfield, in the county of Hampden and State of Massachusetts, have invented a new and useful Improvement in Woven-Wire Hammocks, of which the following is a specification and description.

The object of my invention is to provide a hammock made of woven wire, with each end secured to a suspending-bar adapted to have the suspending-cords attached thereto, and with the two sides of the hammock, at its edges, elevated above the middle portion when the hammock is in its natural position when suspended; and I accomplish this by the means substantially as hereinafter described, and illustrated in the accompanying drawings, in which—

Figure I is a plan view of a hammock made according to my invention. Fig. II is a transverse section of the same at line A of Fig. I. Fig. III is a longitudinal vertical section at line B of Fig. I, showing one modification of securing the ends of the woven wire to the suspending-bars. Fig. IV is a longitudinal vertical section at the sameline, showing another modification of securing the ends of the woven wire to the suspending-bars; and Fig. V is a plan view of the woven wire, showing substantially its form preparatory to being secured to the end suspending-bars in order to give the side edges of the hammock a more elevated position than its middle portion when suspended.

In the drawings, 4 represents a web, made of ordinary woven-wire, similar to the woven-wire mattresses in common use, but made of a suitable width to be used as the ordinary cloth or netted hammocks. After the web is woven I make its middle portion longer than its two side edges, 5, in order to give to the web a concave form on its upper side in its cross-section, to obviate the liability of the person occupying it to roll out on either side, and I may give this form to the web by stretching it after being woven, so that its ends will assume a curved form, as shown in black lines in Fig. V, or an angular form, as shown in dotted lines in the same figure. I then take a bar, as 1, one for each end of the web, of any suitable form in its cross-section, and provided either with a transverse external recess, as 2, near each end, or with a ring or hook fastening, as 9, to which

to secure the suspending-cords, and I make a groove, as 6, in each bar, and secure each end of the web in the said groove of its respective bar 1, with its extreme edge straight and parallel with the edge of said groove, and I then force a binding cleat or rod, as 3, made to approximately fit said groove, firmly thereinto and against the end of the web, and secure it by nails or screws, so that the extreme end of the web is firmly clamped between the bed of the groove and the binding cleat or rod.

Each bar, as 1, may be grooved to receive the end of the web and the binding-cleat on the side toward the web, as shown in Fig. III, or the web may be secured to the bar on the side of the latter opposite the web, as shown in Fig. IV, in which case a longitudinal slot or opening, as 7, may be made through the bar 1, and the latter provided with a groove, as 6, and binding-cleat, as 3, on its outside, and the end of the web may be passed through this slot 7 and secured with its extreme edge straight and parallel with the cleat, the latter being forced into its groove 6 on the outside of the bar and secured with nails or screws, as before, with the end of the web firmly clamped between the binding-cleat 3 and the bed of the groove, as shown in Fig. IV. By making one or both ends of the wire web 4 of this curved or angular form, so that the middle portion of the web is longest, and then securing it in the bars, with its end edges straight, the side edges 5 of the web are made shorter, to a greater or less degree, than its middle portion, and are therefore held at a higher elevation than the middle portion, and the web is given approximately the same concave or hollow form in its cross-section as is given to the best cloth or netted hammocks, and which is desirable to secure the greatest comfort to a person occupying the hammock.

If desired, the wire from which the web is woven may be tinned, galvanized, or treated with any other desired preparation, in order to protect it from the action of the weather and prevent its rusting.

It is evident that a hammock having its web made of woven wire, as above described, will be much more durable than a hammock made of any textile fabric, and is much more comfortable for use, because it will retain its shape, and on account of the elevation of its side edges

above its middle portion a person occupying it would be less liable to roll out at the side.

Having thus described my invention, what I claim as new is—

5 1. An improved hammock, consisting of a web made of woven wire and a suspending-bar secured to each end thereof, and provided with fastenings by which each said bar may be secured to cords to suspend the hammock from each end, substantially as described.

10 2. In an improved hammock, a web made of woven wire and having its two side edges shorter than its middle portion, and secured at each end to a suspending-bar, whereby the web of the hammock will assume a dishing or approxi-

mately concave form on its upper side when suspended by said bars at the ends, substantially as described.

15 3. In an improved hammock, a woven-wire web, in combination with two suspending-bars, one at each end of the web, and each bar provided with a longitudinal groove, and a binding-cleat adapted to approximately fit said groove and be secured therein to said bar to firmly clamp the end of the web to said bar, substantially as described.

FREDERICK A. NELSON.
